(57) **CLAIM**

The ornamental design for an oxygen generator for a skin care system as shown and described.

DESCRIPTION

FIG. 1 is a rear elevational view of an oxygen generator for a skin care system, in accordance with the present design;

FIG. 2 is a left side elevational view thereof;

FIG. 3 is a front elevational view thereof;

FIG. 4 is a right side elevational view thereof;

FIG. 5 is a top plan view thereof;

FIG. 6 is a bottom plan view thereof; and,

FIG. 7 is a perspective view thereof from the rear and left side.

The portions enclosed by broken line depict environment only and do not form part of the design.
